VALVE CLOSED CONTAINER

Ralph M. Berglund, Seattle, Wash., assignor to
 American Can Company, New York, N. Y., a
 corporation of New Jersey

Application August 23, 1944, Serial No. 550,745

5 Claims. (Cl. 220—44)

1

This invention relates to vent-type containers for food and the like and has particular reference to a yieldable relief valve molded to a perforated wall of a can to be used with containers filled with products which develop gases, the valve permitting the escape of such gases through a vent opening while at the same time preventing the ingress of air into the canned product.

An object of the invention is the provision of a yieldable escape valve which may be molded in the perforate wall of a can, for example in the wall of an end and in a position overlying a vent opening, to secure the valve to the can end by elastic threads extended through the perforations, such an end being adapted for use in cans filled with cheese and the like in which there will be a temporary venting of excess gases generated within the filled can.

Another object is the provision of a yieldable vent valve for can ends including a disc of rubber and a ring of rubber located on opposite walls thereof and joined together by threads of rubber passing through a plurality of spaced perforations in the can end and surrounding a centrally disposed vent opening, the threads of rubber being stretched by developed gas pressure within the filled can to lift the valve disc for releasing the gases through the vent opening and between the stretched threads.

A further object is the provision of such a valve which is formed as a unit in a perforated panel of a can end and which panel thereafter is reformed in the region between the vent opening and the perforations to provide a predetermined gas barrier in the can end, such reformation imparting an initial tension in or a preloading of the valve to increase the yield point of pressure at which the valve will release gas from the product inclosed within a sealed can of which the valve is a part.

Numerous other objects and advantages of the invention will be apparent as it is better understood from the following description, which, taken in connection with the accompanying drawings, discloses a preferred embodiment thereof.

Referring to the drawings:

Figure 1 of the drawings is a vertical sectional view of the upper portion of a container embodying the present invention, showing a relief valve in its normally closed position;

Fig. 2 is an enlarged sectional view through the central portion of the container illustrated in Fig. 1, with the valve lifted to an open or gas releasing position;

Fig. 3 is a fragmentary top plan view of the 55 Fig. 3).

2

container with parts broken away and with parts of the valve in section;

Fig. 4 is a view similar to Fig. 1 showing a modified form of the invention; and

5 Fig. 5 is a view similar to Fig. 2 showing the valve of the modified form lifted to an open position during the venting of gases.

In the practice of canning foods, products such as cheese and the like are frequently packed in 10 sheet metal cans and allowed to age or ripen while sealed therein. During this aging or ripening process gases, especially carbon dioxide, are formed. These gases accumulate within the sealed container and create an excess internal 15 pressure. Unless the pressure is relieved, the walls of the can are bulged outwardly and the pressure may even cause straining or breaking of the seams or joints of the can.

Hence a relief or escapement valve has been 20 found to be desirable and indeed necessary to vent such excess internal pressure but at the same time the canned product must not be subjected to the ingress of air.

As a preferred embodiment of the present invention, the drawings illustrate a sheet metal can comprising a tubular body 11 which may be of 25 desired size or shape. A top can end 12 is secured to the upper end of the body 11 in an end seam 13. This seam is of the conventional double seam form being lined with a gasket or sealing compound to render it hermetic.

The can end 12 is formed with a depressed panel 14 having a raised central wall part 15 which preferably is spaced below the top edge of 30 the end seam 13. The wall part 15 has a centrally disposed vent opening 16 surrounded by a plurality of spaced perforations 17 which are concentric with the vent opening (Fig. 3).

The exterior surface of the wall part 15 provides a valve seat for a yieldable relief or escape valve 18. Such a valve is made of rubber or similar yieldable material which preferably is molded into shape and in position directly on the wall part 15 of the can end 12 preparatory to seaming 40 the end to the body 11.

The valve 18 comprises a disc-like member 22 having a dome shape exterior and adapted to overlie the vent opening 16 and also the perforations 17. Valve 18 also includes a ring of rubber 50 23 which is located on the opposite surface or interior wall of the panel. This ring of rubber preferably is formed with a semi-circular cross section (Figs. 1 and 2). The ring 23 covers the perforations 17 on the inside of the can (see also Fig. 3).

The valve 18 is retained in place on the panel 14 largely by integrally formed peripherally spaced necks of rubber 24 extending through the perforations 17, each neck passing through and completely filling its perforation. The rubber necks 24 form connecting parts between and are preferably integrally formed with both the dome shaped member 22 and the rubber ring 23.

The valve 18 preferably is prepared as a unit part of a can end top 12 prior to joining such an end with the can body. This includes molding the valve 18 in place on the perforated panel 14 and this may be done while the wall part 15 is flat. This wall part thereafter is reformed in the region between the vent opening 16 and the perforations 17 by being pressed preferably into an annular ridge 25 to provide a gas barrier (Fig. 2).

The pressing of the ridge 25 against and into the valve part 22 sets up an initial tension in the rubber. This is referred to as a preloading of the valve. The amount of preloading may be varied by a change in the height of such a ridge or different shapes of barrier may be used, the shape shown in Figs. 1, 2 and 3 being preferred.

It will be understood that a greater preloading of the valve 18 increases the yield point of pressure at which such a valve will release gas from the product inclosed within the sealed can. Figure 2 illustrates the disc member 22 of the valve as it is lifted into open position as by the internal gas pressure which obviously at such a time exceeds the predetermined, preloaded valve pressure setting. Arrows, marked A, indicate the path of travel of the escaping gases. Such gases pass through the vent opening 16 and above the gas barrier 25 escaping outwardly around and between the spaced rubber necks 24. It will be observed that at such a time the valve disc 22 is arched sufficiently to clear the top of the ridge 25 and the threads 24 are stretched so that there is a passage to the outside atmosphere under not only the center but also under the periphery of the valve disc 22.

Following the venting of the excess internal gases from the can that is, when the relieved pressure drops to the preloaded release point, the valve 18 closes. The valve member 22 presses down onto the ridge or gas barrier 25 into its initial position again sealing the vent opening 16 and the product within the can. As further ripening of the product takes place, repeated valve action occurs and venting of gases continues.

Figures 4 and 5 of the drawings illustrate a slightly modified form of the invention. All the details of this modified form are the same as those of the preferred embodiment just described with the exception of the preloading feature. The preloading elements of the modified valve include an annular raised or inclined control edge or flange 27 terminating in and surrounding the vent opening 16. Such an edge is flared and is embedded in the molded valve part 22 as shown in Fig. 4, Fig. 5 showing the venting position.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

other products which develop gases, the combination of a can end having a vent opening and a plurality of spaced perforations surrounding the opening, said end further having an annular ridge located between the opening and said perforations, and a valve united to the can end and overlapping said vent opening and closely fitting said ridge on the exterior of the container, integral portions of said valve extending through and filling the perforations and covering the latter on opposite sides of the can end with a preloaded pressure created by the formation of said annular ridge subsequent to the formation of said valve, said valve being outwardly yieldable under the pressure of gases evolving from the can product to uncover and escape through the vent opening and thence over said ridge thus also exposed, said released gases thereafter escaping between the spaced filled perforations when the valve is lifted at a predetermined gaseous pressure.

2. In a container for preserving cheese and other products which develop gases, the combination of a can end having a central vent opening defined and encircled by an outwardly flared flange, said end further having a plurality of spaced perforations surrounding said opening, and a valve united to the can end and overlapping said vent opening on the exterior of the container, integral portions of said valve extending through and filling the perforations, said valve thereby covering said perforations on opposite sides of the can end with a preloaded pressure in part created by said outwardly flared flange, the said valve being outwardly yieldable under the pressure of gases evolving from the canned product to uncover and escape through the vent opening and thence between the spaced filled perforations when the valve is lifted at a predetermined gaseous pressure.

3. In a container for preserving cheese and other products which develop gases, the combination of a can end having a central vent opening and a plurality of spaced perforations surrounding the opening, and a resilient valve disposed on the exterior of the can end to seal said container by overlapping said vent opening and said perforations, said valve having integral neck portions extending through and filling said perforations, an integral ring portion of said valve connecting with said neck portions and covering said perforations on the interior of the can end for sealing the perforations and for holding the valve in place on the can end, said valve being yieldable outwardly at a predetermined pressure of gases evolving from the product within the container and exerted through the vent opening to lift said valve to thereby allow the gases to escape between the valve neck portions between said perforations.

4. In a container for preserving cheese and other products which develop gases, the combination of a can end having a centrally disposed vent opening and a plurality of circumferentially arranged perforations surrounding and spaced radially outwardly from said opening, and a yieldable valve normally covering said vent opening exteriorly thereof and substantially flush therewith, integral portions of said valve also extending through said perforations to fill the latter and unite the valve to the can end, said valve being outwardly yieldable away from the can end under pressure of gases from the canned product, said gases escaping through the vent opening and thence around and beneath the periphery of the valve between the filled perforations when the valve is lifted by said gas pressure.

I claim:

1. In a container for preserving cheese and valve is lifted by said gas pressure.

5. In a container for preserving cheese and other products which develop gases, the combination of a can end having a centrally disposed vent opening and a plurality of spaced perforations surrounding the opening in radially spaced relation thereto, and a valve united to the can end and normally overlapping said vent opening on the exterior of the container, integral portions of said valve extending through and filling the perforations and merging into an integral ring portion 10 engaging and covering said perforations on the inner surface of said can end, said valve being outwardly yieldable away from the can end under a predetermined pressure of gases evolving from the canned product within the container, thereby uncovering said vent opening to permit said gases to escape through the vent opening and thence radially outwardly between the spaced filled perforations when the valve is lifted by said predetermined gas pressure.

15 RALPH M. BERGLUND.
